UNITED STATES PATENT OFFICE.

JACOB RINTA AND ALEXANDER MATSON, OF WEST FITCHBURG, MASSACHUSETTS.

BOILER-FEEDER.

1,264,861.

Specification of Letters Patent. Patented Apr. 30, 1918.

Application filed August 16, 1917. Serial No. 186,636.

To all whom it may concern:

Be it known that we, JACOB RINTA and ALEXANDER MATSON, citizens of the United States, and residents of West Fitchburg, in the county of Worcester and State of Massachusetts, have invented a new and Improved Boiler-Feeder, of which the following is a full, clear, and exact description.

This invention relates to a boiler feed of that type in which water automatically feeds into a secondary tank from the main tank when the water in the boiler reaches a predetermined low level, and then the flow of water to the auxiliary tank is cut off and the water feeds from the secondary or auxiliary tank to the boiler to raise the level thereof to a predetermined maximum.

The invention has for its general objects to improve the construction and operation of apparatus of this character so as to be reliable and efficient in use, comparatively simple and inexpensive to manufacture, install and keep in operative condition, and so designed as to be entirely automatic in operation as long as a supply of water is maintained in the main tank.

A more specific object of the invention is the provision of a feed apparatus of the character referred to which includes a plurality of valves operatively connected with a motor which is actuated by steam from the boiler and which has a float-controlled valve, all of which parts are in a novel arrangement whereby water flows from the main to the auxiliary tank while communication between the boiler and auxiliary tank is cut off through the water feed pipe, and when the water in the auxiliary tank reaches a predetermined height the supply of steam to the motor is reversed, so that the first mentioned valves are operated in such a manner that the water from the main tank is cut off, communication established between the auxiliary tank and boiler for water to flow from the latter, and also communication is established between the steam space of the boiler and the top of the auxiliary tank to equalize the pressure between the two.

An additional object is the provision of an automatic air vent valve which allows the air to escape from the auxiliary tank during the charging thereof.

With such objects in view, and others which will appear as the description proceeds, the invention comprises various novel features of construction and arrangement of

parts which will be set forth with particularity in the following description and claims appended hereto.

In the accompanying drawing, which 60 illustrates one embodiment of the invention and wherein similar characters of reference indicate corresponding parts in both the views,

Figure 1 is a diagrammatic view of the 65 boiler feed apparatus with certain parts in section and indicating the position of the valves when water is feeding to the auxiliary tank from the main tank;

Fig. 2 is a similar view showing the condition of the parts when water feeds automatically from the auxiliary tank to the boiler.

Referring to the drawing, A designates a boiler, B a main water supply tank or reservoir, and C an auxiliary or secondary tank which is normally steam-tight. The bottom of the tank B is connected with a pipe 1 which leads to the tank C, there being in this pipe a valve 2, the movable part of which 75 has an arm 3 provided with a slot 4. An operating rod 5 has a pin 6 which engages in the slot 4, whereby the reciprocation of the rod will swing the arm 3 to open or close the valve 2. The rod 5 is connected with the 80 piston 7 of a steam-actuated motor D, the cylinder 8 of which has its opposite ends connected with steam supply pipes 9 and 10. The pipes 9 and 10 are connected with a two-way valve E located within the secondary 85 tank C, and the steam pipe 11 connects the top of the boiler A with the valve E, so that steam can be admitted to either end of the cylinder 8, according to the position of the movable part 12 of the valve E. 95

The movable element 12 of the valve E has a crank arm 13 which is hingedly connected at 14 with a connecting rod 15, which latter is provided with a longitudinal slot 16 in which engages a pin 17 on the upper arm 100 18 of a bell crank lever 19. This lever is fulcrumed at 20 in the tank C, and its arm 21 has a pin 22 engaging in a slot 23 of a link 24, which is connected at 25 with the float-carrying arm 26, such arm being adjustably mounted at 27 on an arm 28. Projections 29 on the rod 15 limit the swinging movement of the crank arm 13 with respect to the said rod. When the float drops the valve E is so actuated that steam is admitted 105 to the right end of the cylinder 8 of the motor D, and the piston 7 causes the valves 2 to

open, so that water flows by gravity through the pipe 1 from the pipe B to the tank C. The float gradually rises independently of the lever 18 until a certain point is reached, 5 when the said lever is caused to move so that the weight 18^a thereof will soon pass over a vertical dead center line extending through the pivot point 20, when the arm 18 will move suddenly to the left and cause the movable element 12 of the valve E to be shifted through the connecting means 15 and 13. Steam is now admitted to the left end of the cylinder 8 through the pipe 9, and the dead steam passes out of the right end through 10 the pipe 10 and exhaust pipe e, which is connected with the valve E and leads out of the tank C to the atmosphere. When the piston moves to the right the valve 2 is closed, so that the supply of water is cut off.

15 20 The water flows from the secondary tank C to the boiler A through a pipe 30 which includes a valve 31, the movable part of which has an arm 32 similar to the arm 3 of the valve 2, but the valve 31 is adapted to be opened while the valve 2 is closed, or vice versa. Thus, when the motor D closes the valve 2 the valve 31 will be opened and water will flow from the tank C to the boiler A. To facilitate this flow a steam equalizing 25 30 pipe 33 connects the pipe 11 with the top of the secondary tank C, and in this pipe 33 is a valve 34 having a crank arm 35 similar to the crank arm 32 and operatively connected with the motor D. The valve 34 opens or closes with the valve 31 simultaneously.

35 To relieve the pressure in the tank C while the water is flowing into it, a relief valve F is employed. This comprises a cylinder 36 having a vent opening 37, and slideable in 40 the cylinder is a piston 38 having a vent opening 39. The piston is urged downwardly by a lever 40 having a weight 41, although other means may be provided for this purpose. When the boiler pressure is 45 cut off from the tank C, the piston 38 drops, so that the port 39 registers with the port 37, and air can flow out of the tank. As soon as the tank is filled and is again connected with the boiler through the equalizing pipe 33, the boiler pressure acts on the piston 38 to raise the same, as shown in 50 Fig. 2.

55 In order to fill the boiler directly from the main tank a by-pass 42 is provided between the pipes 1 and 30, and in this by-pass is a manually-operated closing valve 43.

60 From the foregoing description taken in connection with the accompanying drawing, the advantages of the construction and method of operation will be readily understood by those skilled in the art to which the invention appertains, and while we have described the principle of operation, together with the apparatus which we now consider 65 to be the best embodiment thereof, we de-

sire to have it understood that the apparatus shown is merely illustrative and that such changes may be made when desired as fall within the scope of the appended claims.

Having thus described our invention, we 70 claim as new and desire to secure by Letters Patent:

1. The combination of a boiler, a main tank, an auxiliary tank, a valve through which water flows from the first to the second tank, a valve through which water flows from the second tank to the boiler, a steam-actuated motor connected with the valves for opening one while closing the other, float means in the auxiliary tank, a valve in the auxiliary tank for controlling the supply of steam to the motor, and a mechanism between the float means and last-mentioned valve for actuation by the float means to a predetermined point, and then operative independently of the float means to open or close the last-mentioned valve. 85

2. The combination of a boiler, a main tank, an auxiliary tank, a valve through which water flows from the first to the second tank, a valve through which water flows from the second tank to the boiler, a steam-actuated motor connected with the valves for opening one while closing the other, float means in the auxiliary tank for controlling the supply of steam to the motor, an equalizing pipe between the secondary tank and the boiler, and a valve in said pipe and operatively connected with the motor to open and close with the second- 100 mentioned valve.

3. The combination of a boiler, a main tank, an auxiliary tank, a valve through which water flows from the first to the second tank, a valve through which water flows from the second tank to the boiler, a steam-actuated motor connected with the valves for opening one while closing the other, float means in the auxiliary tank a valve for controlling the supply of steam to the motor, a mechanism between the float means and last-mentioned valve for actuation by the float means to a predetermined point, and then operative independently of the float means to open or close the last-mentioned valve, 110 and an automatic relief device on the secondary tank for allowing air to escape when the water flows into the secondary tank. 115

4. The combination of a boiler, a main tank, an auxiliary tank, a valve through which water flows from the first to the second tank, a valve through which water flows from the second tank to the boiler, a steam-actuated motor connected with the valves for opening one while closing the other, float means in the auxiliary tank for controlling the supply of steam to the motor, an equalizing pipe between the secondary tank and the boiler, a valve in said pipe and operatively connected with the 120 125 130

motor to open and close with the second-
mentioned valve, and a weighted vent valve
normally held closed by the boiler pressure
in the secondary tank and adapted to auto-
matically open when the pressure in said
5 tank is reduced at the time of flow of water
thereto from the main tank.

5. The combination of a boiler, a main
10 tank, an auxiliary tank, a valve between the
tanks, a valve between the auxiliary tank
and boiler, a motor connected with the
valves for opening one while closing the
other, a valve in the auxiliary tank and
15 connected with the steam space of the boiler
and to opposite ends of the motor, an ex-
haust conduit leading from the last-men-
tioned valve to the atmosphere, a weighted
lever having a lost motion connection with
20 the movable part of the valve in the auxil-
iary tank and adapted to drop suddenly
after passing a dead center position, a float
in the auxiliary tank united by lost motion
connection with the said lever.

6. The combination of a boiler, a main

tank, an auxiliary tank, a valve between the 25
tanks, a valve between the auxiliary tank
and boiler, a motor connected with the
valves for opening one while closing the
other, a valve in the auxiliary tank and
20 connected with the steam space of the boiler 30
and to opposite ends of the motor, an ex-
haust conduit leading from the last-men-
tioned valve to the atmosphere, a weighted
lever having a lost motion connection with
35 the movable part of the valve in the auxil-
iary tank and adapted to drop suddenly
after passing a dead center position, a float
in the auxiliary tank united by lost motion
connection with the said lever, and a pres-
40 sure equalizing valve between the upper
part of the auxiliary tank and boiler, said
equalizing valve having connection with the
said motor, whereby the equalizing valve
and second-mentioned valve open and close
simultaneously.
